COMBINED BATHTUB AND SHOWER MODULE

Michael Lax, New York, N.Y., assignor to Formica
Corporation, Cincinnati, Ohio

Continuation-in-part of design application Ser. No. 20,337,
Dec. 3, 1969. This application July 1, 1970, Ser. No.
23,791

Term of patent 14 years

Int. Cl. D23—02

U.S. Cl. D23—49

FIG. 1

FIG. 2

FIG. 3

FIG. 4

FIG. 5

FIG. 1 is a front perspective view of a combined bathtub and shower module showing my new design.

FIG. 2 is a cross sectional view taken on line 2—2 of FIG. 1.

FIG. 3 is a cross sectional view taken on line 3—3 of FIG. 1.

FIG. 4 is a cross sectional view taken on line 4—4 of FIG. 1.

FIG. 5 is a cross sectional view taken on line 5—5 of FIG. 1.

The broken line representation of the fixtures in FIGS. 1, 2, 3, 4 and 5 are for the purposes of illustration only.

This is a continuation-in-part of design application Ser. No. D. 20,337, filed Dec. 3, 1969, now abandoned.

I claim:

The ornamental design for a combined bathtub and shower module, substantially as shown and described.
